MACHINES FOR FORMING CARTONS
Edward John Everard Powell, 42 Palace Road,
London SW. 2, England
Filed Dec. 5, 1960, Ser. No. 73,569
7 Claims. (Cl. 93—44.1)

This invention relates to machines for forming cartons from blanks of paper, cardboard or like material. The invention is primarily concerned with cartons which can be sealed by heat sealing methods and is particularly though not exclusively concerned with cartons for containing liquids such as milk or other beverages.

According to the present invention the machine comprises a supporting means such as a rotatable table or endless chain which carries a plurality of non-rotatable formers in spaced relationship around the supporting means, means for feeding a carton body blank to each former, means for folding said carton body blank around the former with one edge of the blank overlapping the other and means for heat sealing the overlapping edges of the carton body. The non-rotatable formers will also incorporate an expandable mandrel which projects beyond the end of the former to co-operate with a closure forming and capping die which forms and places a lid on the body and heat seals the body and closure, so that a carton closed at one end is produced. Preferably the non-rotatable formers are suspended from the rotatable table or support and the expanding mandrel projects below the former to co-operate with the closure forming and capping die which is caused to move to meet the expanding mandrel. The folding heat-sealing, closure forming and capping mechanisms may be actuated by means of suitable cams, hydraulic or pneumatic mechanisms which actuate plungers or their equivalent during the movement of the table supporting means. The heat sealing will be effected by means of electrically heated pressure applying means.

In order that the invention may be fully and clearly comprehended the same will now be described with reference to and by the aid of the accompanying drawings, wherein:

FIGURE 1 is a sectional elevation showing one half of the machine at the point where the blank is loaded on to the body former.

FIGURE 2 is a similar view to FIGURE 1 but showing the point where the formed body is applied with an end closure.

FIGURE 3 is a part sectional plan view of an expanding mandrel.

FIGURE 4 is a part sectional elevation of FIGURE 3.

FIGURE 5 is a detail view showing part of the control means for contracting the mandrel.

FIGURE 6 is a sectional elevation of a modified form of machine for applying insert or push-in type end closures.

FIGURE 7 is a fragmentary sectional enlarged view of a mandrel of the modified machine shown in FIGURE 6.

Referring to the drawings, the machine comprises a central pillar 1 on which is rotatably mounted a table or support 2. Said table or support carries on its underside a plurality of body formers 3 which are non-rotatably mounted beneath the table or support 2, equally spaced around said table or support. The body formers 3 are rectangular in cross-section with radiused corners and secured to the table 2 or other rotating part of the machine are a series of clamps 4 and 5 for each former which hold and fold a blank of material around the body former 3 so that the longitudinal edges of the blank overlap. The front clamps 4 are pivotally mounted about a substantially horizontal axis 6 above the table or

2

support 2 and are pivoted towards and away from the body former by means of a pinion 7 engaged by a toothed quadrant 8 having a lever 9 and follower 10 which engages a cam track 11 which is carried on a fixed member 12 locked at 13 to the central pillar 1. The side clamps 5 are pivoted at 14 about a substantially vertical axis in bearings 15 beneath the table or support 2 and arranged to be moved towards and away from the body former 3 by means of link mechanism 16, in such a manner that they fold the blank so that one edge overlaps the other. The links 16 are carried on a spring-loaded plunger 17 having a follower 18 engaging a stationary cam 19 around a fixed column 20 which surrounds the central pillar 1. Associated with the side of the body former 3 at which the longitudinal edges of the carton body overlap is a pressure member 21 which will be electrically heated and is mounted on a pressure loaded plunger 22 supported in bearings 23 attached to and beneath the table or support 2. At the free end of the plunger 22 is a follower 24 which engages a stationary cam 25 formed on the casing 20 surrounding the central pillar 1.

The carton blanks 26 (FIGURE 1) are fed from a conveyor (not shown) and are positioned mechanically on to a flyer 27 which feeds the carton blanks to the body former 3 and the flyer 27 is pivotally mounted at 28 and passes the blanks 26 from a substantially horizontal or inclined position to a vertical position against the body former 3.

The carton blanks 26 may alternatively be picked up by suction means by the front clamps 4 in which case the flyers 27 are not required. The front clamps operate from a substantially horizontal position to a substantially vertical position.

Electric current may be passed to the presser plate 21 for heat sealing through di-electric control or a slip ring and brush gear indicated at 29 (FIGURE 2) associated with the central pillar 1 and the rotatable table or support 2.

The body former 3 is hollow and accommodates the shaft 30 of an expandable mandrel 31 whose expanding portion 32 projects below the end of the body former, the expansion and contraction of the mandrel 31 being effected by the rotation of the mandrel shaft 30 by means of a pinion 33 which meshes with a toothed member 34 pivotally mounted at 35 on the table or support 2 and having an arm 36 at the end of which is an eccentric stud 37 carrying a follower 38 which engages a stationary cam track 39 on the fixed member 12 locked 13 to the central pillar 1.

Beneath the body former 3 and capable of being in axial alignment therewith is a spring-loaded cam controlled vertical plunger 40 carried in a bracket 41 secured to a further bracket 42 carried in a cross head 43 and slideable or swingable in a horizontal plane from the axis of the central pillar 1. The sliding part of head 43 will be spring-loaded (not shown) in one direction and moved in the opposite direction by means of a follower 44 which engages a stationary cam track 45 formed on or secured to the casing 20 surrounding the central pillar 1. The lower end 46 of the spring-loaded shaft 40 has a follower 47 which rests upon a further cam track 48 formed on or secured to an extended flange 49 of the casing 20 surrounding the central pillar 1. At the upper end of the spring-loaded shaft 40 is a cupped die 50 which has a spring-loaded platform 51 so that closure blanks 52 placed thereon, when pressed against the end of the mandrel 31 and carton body, are folded around said carton body. Expansion of the mandrel 31 presses the end portion of the wall of the carton body and the flange (not shown) of the closure against the wall of the cupped die 50. In this way the closure may be heat sealed on to the carton body and

for this purpose either or both the mandrel 31 or die 50 may be electrically heated. The body forming machine may have 10 or as many as 30 heads, i.e. body formers 3 and the table or support 2 is constantly rotated. It may be rotated in any suitable plane from horizontal to vertical, the plane of ancillary movement conforming accordingly. The plant under present description has its turrets rotating in a horizontal plane.

At the first station, the carton blank will be wrapped or folded around the body former and as it passes through succeeding stations the heat sealing of the carton body takes place and at the station following the wrap round station the closure is applied and heat sealed over several stations, after which the mandrel 31 is retracted, the die 50 lowered and moved to one side on the cross-head 43 so that the carton body closed at one end can be caused to drop off the body former by mechanical or pneumatic means on to the conveyor which takes it to the filling machine.

The body former 3 may be supported against pressure exerted by pressure plate 21 which heat seals the carton body seam by causing the pivotal clamp 4 opposite to engage a cam 53 (FIGURE 2) which prevents its outward movement for part of the rotation of the machine e.g. during the period which heat sealing of the carton body takes place.

The table or support 2 will be driven by means of a suitably positioned electric motor (not shown) and the various cams referred to control the sequence of operations in accordance with the rotation of the table or support.

The expandible portion of the mandrel 31 is shown in detail in FIGURES 3, 4 and 5 and the expanding portion 32 comprises four metal segments 54 complementary to one another and of similar shape to the carton body. The segments 54 are slidably mounted for movement in a radial direction and are interconnected by mechanical means (FIGURE 5) tending to move them radially inwardly into retracted position. The segments are guided in their radial movement by providing them with studs 55 or guides which are slidable in slots 56 in the base member 57 and further the adjacent side edges of the segments 54 are formed with interengaging fingers or the like 58 so that there is no gap between the adjacent segments 54, and even in expanded position they will present a continuous peripheral edge, i.e. pressure face for engagement with the adjacent part of the wall or flange of the end closure. Sealing faces 59 may be toothed, grooved, and/or rubber clothed.

In order to effect expansion of the segments the base 57 is provided with a central recess 60 in which a "four-throw" cam 61 is mounted for rotary movement in direction normal to the radial movement of the four segments 54. Alternatively, hydraulic or pneumatic means can be applied for this purpose. The segments 54 are returned inwardly on reversal of the rotary cam movement by reason of the provision of eccentrically mounted slots 62 in a ring 63 fixed to the shaft 30 on which ring the segments are slidably mounted by means of guiding spigots 64.

The above description describes the application of a cap-fitting closure. Little modification is required to convert the machine to one suitable for applying an inserted or push-in type closure.

FIGURES 6 and 7 illustrate a modified form of machine and mandrel capable of applying this type of closure. In FIGURE 6 upper and lower spaced circular rotatable platforms or tables 65, 66 are provided adapted to be rotated by means of an electric motor (not shown) driving a toothed wheel 67 beneath the lower platform 66.

The lower platform 66 has a plurality of body supporting members 68 each mounted on a spring-loaded shaft 69 at the lower end of which runners 70 engage stationary cam tracks 71 mounted on a base plate 72 of the machine.

The upper platform or table 65 carries a flange 73 formed with a plurality of guide apertures 74 axially 75

aligned with the body supporting members 68 and also in axial alignment with these guide apertures 74 are capping heads 75 which are spring-loaded at 76, cam controlled and capable of axial movement in a vertical plane by means of a follower 77 which engages a cam track 78 provided on a fixed upper flange member 79 keyed at 80 to the central pillar 81. Within the capping head 75 is a reciprocal expanding mandrel 82 whose expansion and contraction is controlled by means of a lever 83 and follower 84 which engages a further cam 85 on the fixed upper flange member 79. Alternatively, hydraulic or pneumatic means can be employed for this purpose.

The guide apertures 74 constitute forming dies for the closures which are laid in blank form (not shown) over the apertures 74, which have radiused guide faces on their upper surfaces causing the blanks to be formed into end closures by the downward action of the collapsed capping head 75. The continued downward movement of the capping head inserts the closure within the carton body "B" after it has been indexed upwardly by the supporting platform 68 until its upper edges have registered against a "step," over which in the downward direction, the closures register within the perimeter of the carton wall, and are heat-sealed to the carton bodies by the expansion of capping head segments (54 in FIGURES 3 and 4) against the heated retaining dies 74. After a due period of pressure and heat dwell the capping head collapses and moves further downward to eject carton in an inverted position in unison with the downward retraction of supporting platform 68 (FIGURE 6).

The undersides of the forming dies 74 are provided with inclined guiding edges or "leads" 86 for leading the top edge of carton body "B" up to its step-stop location.

In order that the closure may be heat sealed to the body the capping head and/or the forming dies will be electrically heated during the rotation of the machine.

What I claim is:

1. A machine for forming cartons comprising a table rotatably mounted about a vertical axis, a plurality of body formers suspended from the underside of said table in spaced relation about said table, each of said body formers comprising a mandrel having radiused corners and a die member associated therewith, a first clamping means for each of said body formers to hold and fold a flat, heat-sealable blank about the associated body former, means for mounting one of said clamps pivotally on a horizontal axis above said table at the front of said body former whereby said one clamp holds and positions a blank for folding about said body former, means for mounting another of said clamps at the side of said body former about a vertical axis relative to said table for moving said other clamp to fold the blank along a longitudinal edge, a stationary pressure member carried by said table which coacts with the side of each body former bearing against the pressure member and the inner overlapping longitudinal seam of said blank and said other clamp to seal said blank, whereafter said die member permanently sets the tube formed from said blank at its radiused corners, blank feeding means for the tubular body blank and blank feeding means for the top closure, table rotating means for moving said table at a constant rate of speed which is synchronized with said blank feeding means for successive formation of tubular, permanently set body blanks on said body formers at a continuous rate, means on said table to automatically form, seal and cap the tubular body in the body-formed position, and means for removing the capped and formed container from the mandrel.

2. A machine as claimed in claim 1 wherein means are provided to swing the mandrel towards and away from the first pair of fixed body-forming clamps.

3. A machine as claimed in claim 1 wherein means are provided to swing the second pair of body-forming clamps towards and away from the mandrel, including a lever and link mechanism in which the links are car-

ried on a lever actuated from a follower engaging a stationary cam around a fixed column which surrounds the vertical axis of rotation.

4. A machine as claimed in claim 1 wherein said pressure member is mounted on a power-loaded swinging arm in bearings attached to and beneath said table and there is provided at the free end of the plunger, a follower which engages a stationary cam formed on the outer casing surrounding the machine.

5. A machine according to claim 1 wherein said mandrel swings to a position above the die member which rises and collapses onto the end of the formed carton body to form and heat seal a cap carried by said die member onto the carton body.

6. A machine according to claim 5 wherein said die member comprises a split, cupped die for carrying and applying the closure blanks, said die being carried in the same peripheral path as that taken by the mandrel when carried at its maximum radius.

7. A machine according to claim 6 wherein the split, 20 cupped die comprises four metal segments complementary to one another and of shape similar to the carton

10

body, the segments being slidably mounted for movement in a radial direction and interconnected by mechanical means tending to move them radially inwardly into sealing position, a housing member provided with slots for guiding said segments in radial direction, said segments being provided with studs slideable in said slots in said housing member, the adjacent side edges of the segments being formed with interengaging fingers to close the gap between the adjacent segments in the retracted position of said segments in order to present a continuous peripheral edge for engagement with the adjacent parts of the end closure causing the latter to make intimate radial contact over the entire carton wall periphery.
